UNITED STATES PATENT OFFICE.

FRANK J. MATCHETTE, OF MILWAUKEE, WISCONSIN.

PNEUMATIC CLEANER.

978,916.

Specification of Letters Patent. Patented Dec. 20, 1910.

Application filed June 1, 1903. Serial No. 159,531.

To all whom it may concern:

Be it known that I, FRANK J. MATCHETTE, a citizen of the United States, residing at Milwaukee, in the county of Milwaukee and State of Wisconsin, have invented certain new and useful Improvements in Pneumatic Cleaners, of which the following is a specification, reference being had to the accompanying drawing, forming a part thereof.

10 The main objects of this invention are to effectively cleanse floors, carpets, walls and other objects by directing a confined blast or current of air or other fluid which may or may not be charged with cleansing or disinfecting substances, over the surfaces of such objects, and to catch and confine or remove the dust and dirt taken up without allowing it to be dissipated and to settle again upon the surfaces from which it has 20 been removed.

It consists in certain novel features of construction and in the peculiar arrangement and combinations of parts hereinafter particularly described and pointed out in the 25 claims.

In the accompanying drawing like letters designate the same parts in the several figures.

Figure 1 is a vertical section on the line 30 1, 1, Fig. 2, of one form of cleaner embodying my invention; Fig. 2 is an inverted plan view of the same; Fig. 3 is a vertical section on the line 3, 3, Fig. 4; Fig. 4 is a plan view of the base or body of the cleaner and 35 a portion of the removable dust catching pan; Fig. 5 is an enlarged vertical section on the line 5, 5, Fig. 1, of the strainer frame, showing a convenient method of securing the end of the strainer cloth thereto; Fig. 6 is 40 a plan view on an enlarged scale, of a part of the strainer frame illustrating the method of holding the edges of the strainer cloth in place snugly against the sides of the strainer frame; Fig. 7 is an inverted plan view of a modified form of the cleaner; Fig. 45 8 is a section on the line 8, 8, Fig. 7; Fig. 9 is a plan view of the base or body, the dust catching pan and strainer being removed; Fig. 10 is a section on the line 10, 10, Fig. 50 9; and Figs. 11 and 12 are inverted plan views showing modifications hereinafter referred to.

Referring to Figs. 1 to 6 inclusive, illustrating one of the various forms in which my invention may be embodied, *a* is the base or body of the cleaner, which may be con-

veniently cast in the form of an oblong box open at the top and having on its under side or face, open transverse blast channels or cleaning grooves *b b*, and open intercepting channels or grooves *c c*, alongside of or surrounding said blast channels and communicating therewith, as shown in Fig. 2. The number and arrangement of the blast channels may be varied, for instance, as follows:—One or more blast channels or cleaning grooves may be provided, and these may be made straight or sinuous as shown in Fig. 12, and arranged more or less transverse to the travel or movement of the cleaner, as shown in Figs. 2, 7, and 11, provided that the working face of the base is spanned or traversed by one or more channels. Each channel may be made to extend entirely across the base, as shown in Figs. 2 and 7, or a series of shorter channels, as shown in Fig. 11 may be used with the same effect, each of the shorter channels overlapping or extending by the adjacent channel or channels, so as to cover a transverse space equal to the length of the longer channel or channels, or to the width from end to end of the working face of the cleaner.

The arrangement of channels or grooves shown in Fig. 2 has been found in practice 85 convenient and effective. In this arrangement two blast channels are arranged parallel with each other and slightly oblique to the transverse axis of the cleaner, and the intercepting channels are both connected at 90 opposite ends of the cleaner with one end of each blast channel.

A tubular bail *d* is pivoted in the ends of the base or body *a*, and terminates in blast nozzles *e*, which open into and are directed 95 lengthwise of the channels *b*, one nozzle communicating with one of said channels at one end thereof, and the other nozzle communicating with the opposite end of the other channel. To the bail *d* is centrally attached 100 a tubular handle or arm *f*, for operating the cleaner and supplying compressed air or gas with or without other detergent, cleansing or disinfecting substances, to the cleaner. The bail *d* is provided on each side of its 105 fluid supply connection with a cock or valve *g*, by which the supply of air or other cleaning agent to each nozzle is regulated or cut off. Obviously a single controlling and regulating valve might be provided in the 110 fluid supply connection *f*, but this would not afford means of regulating and cutting off

the supply of compressed air or other cleaning agent to each blast channel independently of the other channel.

The intercepting channels *c* join the blast channels *b* adjacent to the nozzles *e*, and at their junction therewith are preferably directed the same way as the nozzles, so that the jet of air or gas issuing from each nozzle will act as in an ejector to draw air or gas from the channels *c*. At their ends opposite the blast nozzles the channels *b* communicate with upturned passages *h*, which open laterally into the ends of the box or chamber on the upper side of the base or body *a* above its bottom, as shown in Figs. 1 and 3.

A dust pan or receptacle *i*, which may be conveniently made of sheet metal, is removably fitted in the body or base *a*, and is provided at the ends with openings registering with the openings at the upper ends of the passages *h*. Above these openings the dust receptacle is provided with a device for separating the dust from the dust laden air and permitting the air freed from dust, to escape freely. For this purpose zigzag strainer *j* and a plain screen *k* of coarser mesh, may be employed. The screen *k*, which may be made of wire, is supported horizontally by an inwardly projecting ledge in the pan or receptacle *i*, above the openings from the passages *h*. The zigzag strainer consists of cloth stretched back and forth over two rows of alternating parallel bars *l*, in a frame *m*, which is removably fitted in the upper part of the dust pan or receptacle *i* above the screen *k*. At its ends the strainer cloth is fastened and held snugly against the ends of the frame *m*, as shown in Figs. 1 and 5, by rods *n*, inserted in hems of the cloth and engaged with hooks *o* on the ends of the frame. At its sides the cloth is held in place against the sides of the frame *m* by cords *n'* drawn through hems *o'* in the cloth and into notches or depressions in the ends of the bars *l*, as shown in Fig. 6. The cleaner may however, be provided with other air straining devices, or the dust laden air may be otherwise disposed of.

In the operation of the cleaner constructed as hereinbefore described, compressed air or other cleaning agent being turned on and the valves or cocks *g* *g'* opened, the cleaner is moved back and forth over the surface of the carpet or other object to be cleaned. Blasts or strong currents of air or gas being directed by the nozzles across the surface to be cleaned, and confined and intensified by the channels or grooves *b* *b'*, take up dust and dirt on the surface exposed to said channels and carry them upward through the passages *h* into the receptacle *i* underneath the screen and strainer, which separate the dust and dirt from the air, and permit the air to freely escape. The larger particles of dirt are caught by the screen *k*, which is of

coarser mesh than the strainer cloth, and are thus prevented from entering and lodging in the spaces between the folds of the strainer cloth and thereby clogging the same. The strong blast or current produced by the nozzles in the channels *g*, entrains or draws air from the intercepting channels *c*, tending to produce a vacuum therein, so that dust and dirt which might otherwise escape from the blast channels or cleaning grooves *b* and *b'* be blown into the room, are caught in said intercepting channels and returned into said blast channels.

Under some conditions, as for example when strong air blasts are used, and the base of the cleaner forms with the surface to be cleaned a comparatively tight closure around the channels or grooves in said base, a sufficient vacuum will be produced in the intercepting channels *c*, to prevent or interfere with the free movement of the cleaner. To obviate this, the blast channels *b* are restricted more or less at or near their outlet ends, as shown at *p* in Figs. 1, 2 and 3. This restriction or obstruction of the blast channels causes some air to escape from each of said channels into the intercepting channels *c*, thereby forming between said channels a thin film of air on which the base of the sweeper rides and moves with the greatest freedom.

While for general cleaning purposes compressed air is usually employed, other elastic fluids or gases may be used, and for certain purposes such as cleaning windows or hard floors, the air or other gas may be charged with detergent, abrading, polishing or disinfecting substances.

Referring to Figs. 7 to 10 inclusive, showing another form in which my invention may be embodied, the intercepting channels or grooves *c'* do not connect with the blast channels *b'*, but communicate at both ends through upturned passages with the dust catching receptacle *i* above the bottom thereof, as shown in Fig. 8. In other respects the apparatus is substantially the same as that hereinbefore described and shown in Figs. 1 to 6 inclusive, except that in place of the two valves or cocks *g* *g'*, a single regulating and controlling valve or cock *g'* is provided in the tubular arm or handle *f* of the cleaner, as shown in Fig. 10.

In Fig. 11, two slightly oblique blast channels *b* *b'* are shown, overlapping or extending a short distance by each other at their inner ends, where they communicate with upturned passages or openings *h*.

In Fig. 12 a sinuous or tortuous blast channel *b* is shown as extending across the base with a blast nozzle *e* at one end and a discharge opening *h* at the other.

Various changes in the details of construction and in the arrangement of the component parts of the apparatus other than those

hereinbefore specifically mentioned may be made, without departing from the principle and intended scope of the invention.

1. claim:

- 5 1. A pneumatic cleaner comprising a base adapted to rest upon the surface to be cleaned and having on its under side an air conducting channel of relatively greater length than width and height and extending 10 transversely to the line of normal movement of the cleaner, the opposite walls of the channel at their lower ends terminating substantially in the same plane so as to cause an air current to traverse the channel in the direction of the length thereof, and a tubular air conducting member in communication with said air channel and having a swiveled connection with the base at the point of such communication, substantially as described.
- 15 2. A pneumatic cleaner comprising a base having a blast-confining channel in its bearing face, said channel having inflexible walls, its greatest length being in the direction of travel of air therethrough, and transverse to the movement of the cleaner, said base being also formed with air inlet and outlet openings arranged to direct an air blast through said channels lengthwise thereof, transverse to movement of the cleaner, 20 and in contact with the surface to be cleaned, and a tubular bail provided with a nozzle opening into said inlet opening, substantially as described.
- 25 3. A pneumatic cleaner comprising a base having transverse blast-confining channels in its bearing face, and a dust catching chamber communicating with one end of one channel and the opposite end of the other channel, and nozzles opening into said 30 channels and arranged to direct air blasts lengthwise thereof across the surface to be cleaned toward the openings into the dust catching chamber, substantially as described.
4. A pneumatic cleaner comprising a portable base having in its bearing face a blast channel formed with inflexible walls and an intercepting channel arranged alongside thereof and communicating therewith, said blast channel having an outlet opening and 45 an inlet opening arranged to direct a blast of air lengthwise thereof across the surface to be cleaned toward the outlet opening and to draw air from the intercepting channel, and a tubular bail provided with a nozzle 50 which opens into the inlet of said blast channel, substantially as described.
5. A pneumatic cleaner comprising a portable base having in its bearing face a blast channel formed with inflexible walls and 55 intercepting channels surrounding and communicating with said blast channel, which has an outlet opening and an air inlet opening arranged to direct an air blast lengthwise thereof and to draw air from the intercepting channels, substantially as described.

6. In a pneumatic cleaner, the combination of a portable base having a transverse blast-confining channel in its bearing face and intercepting channels surrounding and communicating with said channel, and a 70 dust catching receptacle, communicating with said channel at one end thereof, and provided with a strainer to retain the dust and permit the escape of air, and a nozzle opening into said channel, arranged to direct an air blast lengthwise thereof toward the opening into said dust catching receptacle and transverse to the movement of the cleaner, substantially as described.

7. In a pneumatic cleaner, the combination of a portable base having open transverse blast channels and intercepting channels or grooves surrounding them, said intercepting channels communicating with each of the blast channels, and blast nozzles opening 85 into the blast channels adjacent to the junction therewith of the intercepting channels, substantially as described.

8. In a pneumatic cleaner, the combination of a portable base provided in its working face with a blast confining channel having inflexible walls and a dust outlet and an intercepting channel on each side thereof and in communication therewith, and a compressed air supply nozzle communicating 90 with said blast confining channel, arranged to direct an air blast therein transversely over and against the surface to be cleaned, substantially as described.

9. In a pneumatic cleaner the combination of a portable base provided with open transverse channels, each having an outlet at one end thereof, and a tubular bail terminating in nozzles which open into the other ends of said channels, substantially as 100 described.

10. In a pneumatic cleaner the combination of a portable base having a transverse blast-confining channel opening on one side through its under face, and a dust catching 110 receptacle on the upper side, said channel extending upwardly at one end and opening into said receptacle above the bottom thereof, a blast nozzle opening into the opposite end of said channel to direct an air blast 115 through said channel transverse to the movement of the cleaner and in contact with the surface to be cleaned and through the opening at the other end and a screen covering said dust catching receptacle, substantially as described.

11. In a pneumatic cleaner, the combination of a portable base having a transverse blast-confining channel in its bearing face and extending upwardly at one end, and 125 dust intercepting channels surrounding and communicating with said channels, a removable dust catching receptacle with which said blast channel communicates at its upwardly extending end, an air inlet 130

nozzle opening into said channel and arranged to direct a blast lengthwise thereof toward the opening into said receptacle and transverse to the movement of the cleaner, 5 and a strainer covering said receptacle, substantially as described.

12. In a pneumatic cleaner, the combination of a portable base having open blast channels on the under side and a dust receptacle on the upper side, each of said channels extending upwardly at one end and communicating with said receptacle above the bottom thereof, blast nozzles directed into opposite ends of said channels 15 and a removable strainer covering said receptacle, substantially as described.

13. In a pneumatic cleaner the combination of a portable base having open blast channels and surrounding intercepting 20 channels or grooves in the under side and a dust receptacle on the upper side, each of said blast channels extending upwardly at one end and opening into said receptacle and connected at the opposite end with the 25 intercepting channels, blast nozzles opening into said blast channels at the ends with which the intercepting channels are connected, and a strainer covering said dust receptacle, substantially as described.

30 14. In a pneumatic cleaner, the combination of a portable base having open blast channels, each provided with an outlet opening and formed with dust intercepting channels surrounding and in communication 35 with each of the blast channels, and a tubular bail terminating in nozzles which open into the blast channels, substantially as described.

15. In a pneumatic cleaner, the combination of a portable base having a dust receptacle and formed with a transverse blast confining channel in its bearing face, ex-

tending upwardly at one end and opening into the receptacle above the bottom thereof, a compressed air supply nozzle opening into the other end of said channel and a strainer in the air outlet from said dust receptacle, substantially as described. 45

16. In a pneumatic cleaner, the combination of a portable base having a dust receptacle, a transverse blast-confining channel in its bearing face opening at one end into said receptacle, and transverse dust-intercepting channels arranged on opposite sides of the blast-confining channel and in communication with said dust receptacle, a compressed air supply nozzle opening into the opposite end of the blast-confining channel, and a strainer in the air outlet from said dust receptacle, substantially as described. 50 55

17. In a pneumatic cleaner, the combination of a portable base having a plurality of prolonged comparatively narrow blast-confining channels formed in its bearing face and extending transversely to the normal line of travel of the base and a plurality of dust intercepting channels surrounding and in communication with each of the blast channels, a compressed air supply nozzle opening in one end of each of said blast-confining channels, and an outlet for the air and dust at the opposite ends of said channels, said base having rigid intervening walls between the blast channels to afford a rigid supporting bearing-face to the base substantially as described. 60 65 70 75

In witness whereof, I hereto affix my signature in presence of two witnesses.

FRANK J. MATCHETTE.
